Patented May 29, 1917.

UNITED STATES PATENT OFFICE.

GEORGE L. PIERCE, OF BROOKLYN, NEW YORK, ASSIGNOR TO A. G. SPALDING & BROS.,
OF NEW YORK, N. Y., A CORPORATION OF NEW JERSEY.

GOLF-BAG.

1,227,657.

Specification of Letters Patent. Patented May 29, 1917.

Application filed April 1, 1912. Serial No. 687,557.

To all whom it may concern:

Be it known that I, GEORGE L. PIERCE, a citizen of the United States, residing at Brooklyn, in the county of Kings and State 5 of New York, have invented certain new and useful Improvements in Golf-Bags, of which the following is a specification.

My present invention relates to an improved golf-bag adapted to have some or all 10 of the following features and advantages:

The clubs are kept apart and so are prevented from striking and battering one another. The bag is kept extended so that its mouth does not sag toward its bottom. The 15 means for accomplishing the above may be made independent of the bag so that it may be removed from or applied to the bag at will. These and other features and advantages of my improvements will be understood by those skilled in the art from an 20 understanding of the following specification in connection with the drawings.

These show only one of the specific embodiments which my improvements are adapted to take. Figure 1 is a side elevation of a golf-bag having my improvements incorporated therewith; Fig. 2 is a vertical mid-section of the devices of Fig. 1; Fig. 3 is a side elevation of the devices constituting my improvement 25 shown removed or detached from the bag; Fig. 4 is a plan view on an enlarged scale of the top of the bag and improvements of Fig. 1, a portion of said figure being broken away to reveal the underlying structure, and Fig. 5 is a plan view of a detail intended especially to illustrate the part hereinafter described as the spider.

I will now describe the specific devices of the drawings.

40 1 is a golf-bag of any usual or preferred construction; 2 is a rod ordinarily of wood about the length of the bag,—in this case being somewhat longer so that its upper end projects above the top of the bag to serve as 45 a stick for the player to lean on.

3—3 (see Fig. 4) are golf-club separating members secured about the rod 2 serving to keep the clubs apart and prevent them from rattling about in the bag and damaging one 50 another.

The members 3 in the particular bag shown consist of a piece of canvas or other fabric 4 folded into loops secured by tacks 5 to the rod 2 to project radially therefrom. The adjacent walls of each fold may be 55 stitched together at their base 6 (Fig. 4).

7 (Figs. 2 and 4) is a similar folded piece of leather or other heavier and stronger material which borders the upper edge of the fabric 4. 8 is a leather collar surrounding 60 the club separating members 3, and is shown secured to them by the rivets 9 (Fig. 4).

10 is a metal spider best shown in the detailed view thereof in Fig. 5, and consists of a hub 10^a received snugly in surrounding position on the rod 2 (compare Fig. 2), and having radial arms whose outer ends have laterally extending perforated feet 10^b riveted to the collar 8. This collar 8 is preferably of such diameter that it fits snugly the 65 mouth of the golf-bag immediately under an inwardly directed annular shoulder portion 1^a (Fig. 2) around said mouth, said shoulder portion being formed, for instance, by the inner leg of a binding member which covers 70 the mouth-edge portion of the bag.

Further both said collar 8 and the mouth of the bag may have perforations 11 through which a lace or cord 12 (compare Figs. 1 and 4) is adapted to be passed to secure these 80 parts together.

Since the rod 2 is intended to rest on the bottom of the bag or substantially so, it follows that it upholds the mouth of the bag and prevents the bag from sagging; because 85 at its upper end said rod engages the mouth of the bag as above described.

14 is a disk on the lower end of the rod 2 against which are received the ends of the golf-clubs, thereby saving the bottom of the 90 bag from their direct impact, and further serving as a foot or support for the entire device, should it be desired to remove it from the bag as in Fig. 3.

The stiff arms 10 of the spider keep the 95 rod 2 central with the golf-club receiving loops 3 open.

What I claim as new is:

In combination with a golf-bag having an inwardly extending annular shoulder at its 100

mouth, a rod adapted to be received centrally in said bag, a plurality of separating members forming pockets between said rod and said bag, and a retaining collar attached to said rod and adapted to fit snugly the mouth of the bag and under the said inwardly extending shoulder.

In testimony whereof I affix my signature in presence of two witnesses.

GEORGE L. PIERCE.
